UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A LADY'S WALKING-SKIRT.

SPECIFICATION forming part of Design No. 15,100 dated June 24, 1884.

Application filed May 12, 1884. Term of patent 36 years.

To all whom it may concern:

Be it known that I, SARAH JANE SHIELS, of the city, county, and State of New York, have invented and produced a new and original Design for a Pattern of a Lady's Walking-Skirt, (numbered 9,239;) and I do hereby declare that the engraved prints accompanying this specification convey to any one accustomed to using paper patterns a clear understanding of how a garment made up by the pattern will appear.

The design shows a round walking-skirt; a deep front drapery, which exhibits a curved slope at each side, extending from a point some distance below the belt at the left side of the

center, and displays binnings above the curved edges, and also in its back edges; and a deep, full back drapery, that falls in two deep ovals, and exhibits draping plaits in its front edges and loopings at the center.

What I claim as my invention, and desire to secure by Letters Patent, is—

The design for a lady's walking-skirt, as shown in the engraved prints accompanying this specification.

SARAH JANE SHIELS.
